George C. Brown

United States Patent Office.

GEORGE C. BROWN, OF PHILADELPHIA, PENNSYLVANIA.

Letters Patent No. 76,155, dated March 31, 1868.

IMPROVEMENT IN PORTABLE DERRICKS.

The Schedule referred to in these Letters Patent and making part of the same.

TO ALL WHOM IT MAY CONCERN:

Be it known that I, GEORGE C. BROWN, of the city of Philadelphia, State of Pennsylvania, have invented a certain new and useful Improvement in Portable Derricks; and I do hereby declare that the following is a full, clear, and exact description of the construction and operation of the same, reference being had to the annexed drawings, making a part of this specification; in which—

Figure 1 is a perspective view.

Figure 2 is a plan of the derrick-head with the cap C removed.

Figure 3 is a vertical section of derrick-head through line A B.

Figure 4 is a side elevation of the cap C.

Figure 5 is a plan of cap C.

Figure 6 is a side view of the socket S, into which the poles D are fitted.

Figure 7 is another view of the same.

Description with reference to the drawings, in which like letters refer to like parts. Fig. 1 is a perspective view, showing the derrick in position for use, with all the parts in their proper places, showing the cap C screwed on the top of the derrick-head, answering two purposes, *i. e.*, protecting the sheaves E and rope F from the weather, and preventing the rope F from running off of the sheaves E. It is held in place by the screw-bolts G. The sockets S are shown with the poles D fitted into them, and the sockets fitted in the jaws H, where they are held by means of the bolts or pins I. The rope F is rove through the block K, and over the sheaves E in the derrick-head, when the whole is ready for use in raising and lowering heavy bodies. Fig. 2 shows a plan of the derrick-head O, with the sheaves E in the vertical slots L made to receive them, in which they revolve freely, carrying the rope F over the bolt or pin M, shown by the dotted lines, also the jaws H, in which the sockets S are fitted; also the holes N for the screw-bolts G, which hold the cap C in place.

What I claim as my invention, and desire to secure by Letters Patent, is—

The portable derrick, composed of the head, with its cap and sheaves, sockets and legs, the whole arranged as and for the purpose set forth.

GEORGE C. BROWN.
